J. W. WYATT.

ONE LICK BREAD CUTTER AND CAKE CUTTER.

APPLICATION FILED JUNE 16, 1921.

1,424,389.

Patented Aug. 1, 1922.

UNITED STATES PATENT OFFICE.

JOHN WESLEY WYATT, OF LOS ANGELES, CALIFORNIA.

ONE-LICK BREAD CUTTER AND CAKE CUTTER.

1,424,389.

Specification of Letters Patent. Patented Aug. 1, 1922.

Application filed June 16, 1921. Serial No. 473,162.

To all whom it may concern:

Be it known that I, JOHN WESLEY WYATT, a citizen of the United States, residing at Los Angeles, California, have invented new and useful Improvements in One-Lick Bread Cutters and Cake Cutters, of which the following is a description.

The objects of my invention are to provide a cutter that makes a plurality of slices at one stroke and one that may be converted from the form in which the blades are parallel for cutting a rectangular loaf or the like, to the form in which the blades are convergent or radial for cutting a circular loaf, cake, or the like.

I attain these objects by the device illustrated in the accompanying drawing in which—

Figure 1 is an elevation of a convenient wrench for adjusting the spacing of the knives; Figure 2 is a plan of the assembled device broken away to show a part of the features; Figure 3 is a section through the center line of the handle on the line 3 3; Figure 4 is an elevation of the assembled mechanism; Figure 5 is a section on the line 5 5; and Figure 6 is a plan view of the entire structure adjusted to cut a circular object such as a round cake.

Similar numerals refer to similar parts throughout the several views.

The back 1 of the cutter is formed from one piece of spring metal to the shape shown and serves to hold the knives in line and as a place of attachment for the handle and adjusting levers. The knives 3 and 4 are mounted loosely on the spring rod 2 which is threaded from both ends almost to the center. The center knife 3 has an enlarged heel 3^a and this knife is firmly fixed in the back 1 and on the rod 2 by means of the pin 4 which passes through all of these parts and holds them together. The knives 4 4 are maintained at equal spacings at all adjustments by means of the springs 5 5 one of which is slipped over the rod 2 between each pair of adjacent knives. The knives 4 4 and the springs 5 5 are held on the rod 2 by the nuts 6 6 and the spacing of the knives is adjusted as desired by screwing these nuts in or out by means of the special wrench 16, the width of the spac-

ing being read on the scale 1^b inscribed on the back 1. The heels of the knives are square to fit neatly within the back 1 and are retained in position in the back during curvature adjustments by means of the lip 1^a of back 1 fitting into grooves 4^a 4^a in the knives 4 4.

Thus it will be seen that the knives 4 4 are capable of being moved along the rod 2 by the nuts 6 6 and are held at equal distances apart by the equal springs 5 5.

To the back 1 are soldered or welded three pairs of lugs 7 7 provided with hinge pins 6 6 to which are attached the handle and the adjusting levers 15 15. The handle 9 is threaded along its major portion and on this is screwed the sleeve 10. The grip 11 is slipped over sleeve 10 and secured to it by rivets 12 12 so that both must turn together. A split collar 13 13 fits loosely over sleeve 10 and between the lips 10^a and 11^a and is free to turn on the sleeve. The two parts of the split collar 13 are held together by the pins 14 14 which also pass loosely through the levers 15 15. Levers 15 15 are hinged at their other ends to lugs 7 7 by pins 8 8. Thus when the grip 11 is turned the sleeve 10 turns with it and moves in or out along the threads on handle 9. Collar 13 does not turn but is carried toward or away from the back 1, when the grip is turned and this motion is transmitted through the levers 15 15 to the ends of the back 1. The center of the back is fixed to the handle by the pin 8 and consequently movement transmitted to the ends of 1 causes the back to bend about its center carrying the knives and the rod 2 with it, the knives tending to point toward the center of the circle to which the curvature of the back conforms as shown in Figure 6.

When adjusted in this manner the cutter is capable of slicing circular objects such as round cakes, etc.

I claim:

1. A slicer comprising a flexible head, a plurality of adjustably spaced knives mounted thereon, and means for flexing the said head thereby adapting the slicer to cut an elongated article such as a loaf of bread or a round article, such as a cake.

2. A slicer including a plurality of blades,

and means to adjust the blades so that they will assume a position in which they will be parallel or convergent at will.

3. A slicer comprising a flexible head, a plurality of spaced knives mounted thereon, and means for flexing the said head thereby adapting the slicer to cut an elongated ar-

ticle such as a loaf of bread or a round article, such as a cake.

JOHN WESLEY WYATT.
